CATHODE ARRANGEMENT FOR TELEVISION TUBES

Robert R. Thainer, Princeton, N. J., assignor to Radio Corporation of America, a corporation of Delaware

Application January 28, 1946, Serial No. 643,927

5 Claims. (Cl. 313—65)

1

This invention relates to television tubes of the image orthicon type, such as is disclosed in the application of Paul K. Weimer, filed September 16, 1944, Serial No. 554,494, now U. S. Patent 2,433,941, issued January 6, 1948, but it is not limited thereto.

In the image orthicon of the construction shown in said application, the light from the thermo-active surface of the gun cathode is projected onto the photocathode through the glass target and produces an effect comparable with that of the image projected thereon from the object being televised, particularly at low illumination of such object.

It is an object of this invention to arrange the cathode so the electrons therefrom can be projected through the grid aperture without the light reaching such aperture.

Another object is to face the cathode surface away from the aperture in the grid toward an electron mirror, which reflects the electrons, but not the light from the cathode, through the aperture.

Other objects will appear in the following specification, reference being had to the drawings, in which:

Fig. 1 is a cathode beam tube embodying my invention.

Fig. 2 is a modification of the construction of Fig. 1.

Referring to Fig. 1 of the drawing, an image orthicon such as disclosed in said application of Paul K. Weimer is modified so as to embody my invention, but by way of example only. The cathode beam tube consists of an envelope 1 having a photocathode 2, electrode 3, glass target 4 and collecting screen 5 for producing a charge image on the glass target. On the other side of the glass target from the screen 5 is positioned the decelerating ring or lens 6. At the other end of the tube is the gun comprising a cathode 11, a grid 10, and a first anode 7. The first anode 7, has a front surface 8 which constitutes the first dynode of the multiplier. The other dynodes illustrated in said Weimer application are indicated as a unit 9 and are not shown in detail as they, per se, are not part of this invention. Inside the first anode 7 is the grid 10. The grid 10 and first dynode 8 have the usual small apertures for forming the beam. Instead of positioning the cathode 11 so as to face towards the grid aperture, I reverse it so that the incandescent and thermo-active end 12 faces in the opposite direction and is shielded from photocathode 2 by the opaque portions of the cathode 11 and electrodes 8 and 10. This cathode 11 may be constructed of two cylindrical shells 13 and 14 joined together at one end by an annular wall portion having the incandescent thermo-active surface 12. The heater coil, 60

2

H, is then placed in the annular space between these two cylinders. This leaves an opening 15 for passage of the electrons. Back of the cathode is located an anode screen 16 and further towards the rear of the tube is an electron mirror 17 consisting of an electrode having about the same potential as the cathode, namely, ground, as illustrated in the drawing, or a more negative potential, for suitable reflection of the electrons. The grid 10 in this case may be connected to ground through a positive bias source 18 to provide an accelerating field for urging the electrons reflected from mirror electrode 17 through the tubular cathode 13 and along the beam path toward the target electrode 4. Between the anode 7 and the decelerating lens 6 a wall coating 19 is located on the inside of the envelope. Adjacent the dynode 8 is positioned a persuader electrode 20 for directing the secondary electrons into the remaining dynodes and associated parts indicated at 9. The magnetic deflection unit 21 containing the vertical and the horizontal deflection coils is placed outside the envelope. Longitudinal adjustment of this coil may be made by manipulation of rod 21'. These coils are not individually shown, as they are of the usual construction and their action is well understood. Coil 22 is adapted to be manually adjusted around the axis of the tube to compensate for slight misalignment of the beam. Outside of these two units is placed the electromagnetic focusing coil 23 for focusing the photo-electrons and the beam electrons, as well understood.

The glass target 4, which is translucent, is mounted in a metallic frame 24 containing the collecting screen 5 and this frame is grounded. The decelerating lens 6 is grounded, but it may also be given a slightly higher potential than ground. Photo-electrons are emitted by the photocathode 2 by action of the light image focused thereon from the external object, not shown. These are accelerated by electrode 3 along the field lines of the focusing coil 23 to the glass target 4 through the screen 5. The electrode 3 is made more negative than ground. The horizontal and vertical deflection coils in unit 21 would be connected to the usual saw-tooth generator of line and frame frequencies, respectively. The wall coating 19 and first anode 7 would be connected to suitable positive potentials, as disclosed in said Weimer application and as well known in the art.

The construction shown in Fig. 1 is that disclosed in the application of said Paul K. Weimer, except for the particular form of cathode 11 and associated parts for reversing the electron flow and deflecting the electrons back through the grid aperture.

In the operation of this tube, the incandescent surface 12 of the cathode emits electrons which

are accelerated by positive screen anode 16 away from the thermionic cathode surface 12. These electrons pass through the apertures of this screen electrode to be reflected by the electron mirror 17 and are then accelerated by anode 7 back through the screen 16, the opening in the hollow cylinder 13 of the cathode and the grid aperture, towards the target. The beam electrons not landing on the target to discharge the charge image thereon return to the first dynode surface 8 and bombard electrons therefrom. These are directed around behind the first dynode 8 by the persuader 20 and the more positive potentials of the remaining dynode units 9 toward the deflector unit, the construction of which is shown in said Weimer application. These electrons, of course, enter the annular opening all around the anode 7 and not at one point only, as indicated in the drawing for purposes of explanation. The electrons of the returning beam also scan the surface outside the aperture of the first anode to produce the secondaries.

The electron mirror 17 does not reflect the light from the heated end 12 of the cathode as it does not have a good light reflecting surface and hence light therefrom cannot reach the target. It therefore cannot affect the photocathode 2.

In Fig. 2 I have shown a modification in which the anode 25 accelerates the electrons from the rear end 12 of the cathode at such velocity as to produce secondary electrons by bombarding electrode 25, which are accelerated through the inside channel 15 of the cathode, constructed as shown in Fig. 1. The action of this modification is the same as that of Fig. 1 except that the electrons finally projected through the grid aperture are secondary instead of primary electrons.

Having described my invention, what I claim is:

1. An electron discharge device comprising, an electron gun structure for producing an electron beam along a normal path, a photosensitive electrode positioned transversely to said electron path, said electron gun structure including a thermionic cathode electrode having an electron emitting surface surrounding and spaced from said beam path, and means between said photosensitive electrode and said thermionic cathode surface for shielding said photosensitive electrode from light emitted by said cathode emitting surface.

2. An electron discharge device comprising, an electron gun structure for producing an electron beam along a normal path, a photosensitive electrode positioned transversely to said electron path, said electron gun structure including a thermionic cathode electrode having an annular thermionic emitting surface spaced from and coaxial to said beam path, and means between said photosensitive electrode and said thermionic cathode surface for shielding said photosensitive electrode from light emitted by said cathode emitting surface.

3. An electron discharge device comprising, an electron gun structure for producing an electron beam along a normal path, a photosensitive electrode positioned transversely to said electron path, said electron gun structure including a cathode electrode comprising a tubular member spaced from and coaxial to said beam path and an annular wall portion extending radially from said tubular member, the surface of said wall portion facing away from said photosensitive electrode being thermoemissive, and means between

said photosensitive electrode and said thermoemissive cathode surface for shielding said photosensitive electrode from light emitted by said cathode emitting surface.

4. An electron discharge device comprising, an electron gun structure for producing an electron beam along a normal path, a photosensitive electrode positioned transversely to said electron path, said electron gun structure including a cathode electrode comprising a tubular member spaced from and coaxial to said beam path and an annular wall portion extending radially from said tubular member, the surface of said wall portion facing away from said photosensitive electrode being thermoemissive, and electrode means between said photosensitive electrode and said thermoemissive cathode surface for shielding said photosensitive electrode from light emitted by said cathode emitting surface, an electrode forming an electron mirror facing said thermoemissive cathode surface and positioned on the other side of said cathode electrode from said photosensitive electrode for reflecting electrons from said cathode along said beam path, and an accelerating electrode between said cathode and photosensitive electrode for causing the electrons reflected from said mirror electrode to pass along said beam path through said tubular cathode toward said photosensitive electrode.

5. An electron discharge device comprising, an electron gun structure for producing an electron beam along a normal path, a photosensitive electrode positioned transversely to said electron path, said electron gun structure including a cathode electrode comprising a tubular member spaced from and coaxial to said beam path and an annular wall portion extending radially from said tubular member, the surface of said wall portion facing away from said photosensitive electrode being thermoemissive, and electrode means between said photosensitive electrode and said thermoemissive cathode surface for shielding said photosensitive electrode from light emitted by said cathode emitting surface, an electrode positioned transversely to said beam path and on the other side of said cathode electrode from said photoemissive electrode, said electrode having a secondary electron emitting surface facing said thermoemissive cathode surface for receiving electrons from said cathode, and an accelerating electrode between said cathode and said secondary electron emitting electrode for causing the secondary electrons to pass along said beam path through said tubular cathode toward said photosensitive electrode.
